UNITED STATES PATENT OFFICE.

CLIFFORD E. DUNN, OF PLAINFIELD, NEW JERSEY.

SAFETY-RAZOR.

1,123,714.

Specification of Letters Patent.

Patented Jan. 5, 1915.

Application filed April 14, 1911. Serial No. 621,007.

To all whom it may concern:

Be it known that I, CLIFFORD E. DUNN, a citizen of the United States, residing in the city of Plainfield, county of Union, and State of New Jersey, have invented certain new and useful Improvements in Safety-Razors, for which application for Letters Patent of the United States was filed by me on April 28, 1909, Serial No. 492,708, which application became technically abandoned on May 8, 1910, and of which the following is a full, clear, and exact specification.

My invention relates to safety razors of the type wherein the razor may be stropped without being removed from the razor holder, and it has for its object to provide means whereby a double-edged blade may be used in such razors and both edges of such blade be stropped, particularly while in the holder.

A practicable form of my invention is illustrated in the accompanying drawing, wherein—

Figure 1 is a side elevation of a structure made according to my invention. Fig. 2 is an end elevation thereof. Fig. 3 is a view similar to Fig. 2, enlarged, and illustrating the stropping position of the razor in full lines, and in dotted lines its position when raised preparatory to lowering to such position. Fig. 4 is a vertical cross-section of the device as illustrated in Fig. 3. Fig. 5 is a longitudinal section of the holder and blade and of the slides for carrying the holder, this section being taken on a plane at about the line 5—5 of Fig. 6, and Fig. 6 is a plan view of the holder and blade and of the slides, the guide rails for the slides being indicated in cross-section.

My razor is shown mounted upon a handle 1, and provided with a frame, U-shaped when viewed from the side, and comprising a base-plate 2, to which the handle is attached, and side pieces or arms 3, 4, which are connected by strop-guiding-rollers 5, 6, 7, 8, and by strop-actuated-roller 9. Shifting plates 10, 11, are mounted in the side-frames 3, 4, with which they have a tongue and groove connection, so as to slide therein. Mounted in such plates so as to shift therewith and also to turn therein freely at the same time, is the rod 12, which carries a gear 13 fixed to it at one end, which projects through and beyond arm 4. The rod 12 supports a double-edged blade 14 inter-

mediate the arms 3, 4. Said blade is shown perforated to be received on pins 15 projecting upwardly from a blade-receiving plate 16. Upon which plate 16 the blade is maintained in position by clamping-plate 17 hinged to the receiving plate at 18. The clamping plate is held closed by spring-catch 19.

The sliding-plates 10, 11, fit the frames 3, 4, rather snugly, but so that they may be movable therein. Their intermediate position is that wherein the razor is in shaving position, when the edges of the blade will be in correct shaving relation to the double guard, comprising guards 20, 21, as seen in Fig. 2. The razor is held in such position by catches 22 of springs 23, mounted upon side-frames 3, 4, which enter perforated ears 24 projecting endwise from the sliding plates 10, 11.

When it is desired to strop the razor the catches 22 are released, the plates 10, 11 raised until the razor-blade 14 clears the guard plate, when it is turned to a position transverse of the plane of the double blade seat afforded by the guards, and lowered until the catches 25 enter the ears 24. In this position the gear 13, which rocks the rod 12 and blade-holder 16, 17, is in mesh with a geared sector 26 fixed upon roller 9 and located outside of frame 4. Strop 27 may then be introduced and will pass inside of rollers 5 and 8 and outside of rollers 6, 7, 9. A movement of the strop will cause a rocking of the blade holder as follows: When the strop is moved in the direction of the arrow (Fig. 4), this will cause a counter clockwise movement of roller 9 and sector 26, and a clockwise movement of gear 13, causing the upper edge of the razor 14 to move in the direction of the dotted arrow (Fig. 4), and its lower edge to move in the same angular direction, stropping the respective edges by contact with the strop. A reversal of movement of the strop will cause the above parts to move in the opposite direction and will strop the other edges, and this motion may be changed rapidly.

While I have here illustrated and described a concrete embodiment of my invention, it may be seen that in many respects the same is illustrative merely, as the invention could be embodied in other and equivalent forms. I conceive that it is broadly new to produce a safety razor em-

ploying a double-edged blade wherein the blade may be stropped without removal.

Having thus described my invention what I claim is:

5. 1. A safety razor comprising a frame, a blade carrier and a double edged blade adapted to be clamped therein in shaving position, a guard for said blade, means carried by the frame for guiding a strop and 10 means for moving said blade carrier from shaving to stropping position and means for stropping both edges of said blade simultaneously while carried by said frame.
15. 2. A safety razor comprising a frame, a double guard, means carried by the frame for positioning a strop, a double-edged blade, a carrier for the blade provided with slides, the frame being provided with guides for the blade-carrier located for supporting 20 the frame adjacent the guard or adjacent the strop positioning means, and means for clamping said blade-carrier in either of said positions and the blade in operative position upon said guard or in operative position 25 relative to the strop position.
30. 3. A safety razor comprising a frame, strop-holding and positioning devices located on the frame, a double guard located on the frame, a double-edged blade coöperative with the guard and with a strop traversing said strop-holding means, a blade-carrier and means for shifting the blade carrier to bring the blade into operative position upon said guard and into operative position 35 in respect of said strop and into position for concurrently stropping both edges of said blade while carried by the frame.
40. 4. A safety razor comprising a frame, a double guard, a double edged blade and a movable blade carrier, means for clamping the blade in shaving position upon the guard while in place in said carrier, means for moving said carrier from shaving position to stropping position and from stropping position to shaving position, and means for stropping both edges of said blade simultaneously while in place in said carrier in stropping position.
50. 5. A safety razor comprising a frame, a double guard, a double edged blade and a movable blade carrier, means for clamping the blade upon the guard in shaving position while in place in said carrier, means for holding the blade in position for stropping, 55 means for simultaneously stropping both edges of said blade, and means for moving the carrier and blade from the shaving position to the stropping position.
60. 6. A safety razor comprising a frame, a double guard, a double-edged blade and a movable blade-carrier, means for clamping

the blade upon the guard while in place in said carrier, means for stropping said blade, guide-rollers for said stropping means, a rack connected to one of said rollers, and a pinion connected to said blade-carrier and located in position to coöperate with said rack when the blade is brought to stropping position; and means for moving said blade to stropping position.

65 70

7. A safety razor comprising a frame having a central recess, a double guard and a double-edged blade adapted to coöperate therewith, a movable blade-carrier mounted in a sliding frame, means for clamping said blade in operative position upon said guard, guide rollers adapted to guide a stropping element, means connecting one of said rollers with the blade carrier for oscillating the same, and means located in said recess for 80 stropping said blade while carried by the frame.

75

8. A safety razor comprising a frame having a central recess, a double guard and a double-edged blade adapted to coöperate 85 therewith, means for clamping said blade in operative position upon said guard, means located in said recess for stropping said blade while carried by the frame, guide rollers for said stropping means, a rack connected to one of said rollers, and a pinion connected to said blade-carrier adapted to coöperate with said rack.

90

9. A safety razor comprising a frame, a double blade seat, a double-edged blade and 95 a movable blade-carrier mounted in a slide slideable on the frame in a path transversely of the plane of said double blade seat, means for clamping the blade upon the guard while in place in said carrier, means for stropping 100 said blade, guide rollers for said stropping means, and means connecting one of said rollers with the blade-carrier for oscillating the same.

105

10. In a safety razor, a blade-holder adapted to receive a double-edged blade and expose both its edges, means for clamping the blade in position therein, guards for said blade, rollers for guiding a strop in opposite directions on the razor, means for moving the blade from shaving to stropping position, and a connection between one of said rollers and the blade-holder for rocking same as the strop is moved, to simultaneously stroop both edges of said blade.
